UNITED STATES PATENT OFFICE.

JAMES ALBERT LOOMIS, OF ST. LAWRENCE, SOUTH DAKOTA.

BRACKET-LAMP.

SPECIFICATION forming part of Letters Patent No. 793,884, dated July 4, 1905.

Application filed January 28, 1905. Serial No. 243,118.

To all whom it may concern:

Be it known that I, JAMES ALBERT LOOMIS, a citizen of the United States, residing at St. Lawrence, in the county of Hand and State of 5 South Dakota, have invented a new and useful Bracket-Lamp, of which the following is a specification.

This invention relates to bracket-lamps, and has for its object to simplify and improve the 10 construction and operation of this class of devices.

The present invention relates especially to an improved bracket-lamp which shall be capable of being readily applied to pianos or 15 organs for the purpose of throwing an unobstructed light upon the music in front of the performers, the construction being such that when the device is detached it may be conveniently used as an ordinary table-lamp.

20 The invention consists in the improved construction and novel arrangement and combination of parts which will be hereinafter fully described, and particularly pointed out in the claims.

25 In the accompanying drawings has been illustrated a simple and preferred form of embodiment of the invention, it being, however, understood that no limitation is necessarily made to the precise structural details 30 therein exhibited, but that the right is reserved to any changes, alterations, and modifications to which recourse may be had within the scope of the invention and without departing from the spirit or sacrificing the efficiency of the same.

35 In said drawings, Figure 1 is a perspective view of a bracket-lamp constructed in accordance with the principles of the invention. Fig. 2 is a horizontal sectional view taken 40 through the supporting members of the device and looking in an upward direction. Fig. 3 is a vertical sectional detail view, on an enlarged scale, showing the leaves constituting the bracket collapsed and connected together. 45 Fig. 4 is a bottom plan view, reduced, illustrating a modification. Fig. 5 is a detail side view, partly in section, showing said modification.

Corresponding parts in the several figures

are indicated throughout by similar characters of reference.

The bracket of this device, which is designated B, is composed of a plurality of superimposed leaves 1 1, which in the drawings have been illustrated as consisting of circular disks of gradually-decreasing diameter from the bottom upward—that is, the lowermost or bottom disk is of a diameter exceeding that of the disk supported thereon, which latter is of greater diameter than the succeeding disk, 60 and so on, the uppermost disk being the smallest of all. I would have it understood, however, that this particular construction and arrangement is not absolutely essential, since the several disks may within the scope of the 65 invention be all of the same size and of other than a circular shape. Each of the said disks is connected by pivotal pins 2 2 near its diametrically opposite sides with the adjacent upper and lower disks, with the exception of 70 the top and bottom disks, which of course are connected only with the disks respectively below and above the same. In this manner a simple and neatly-appearing bracket of great strength is formed, which may be readily extended or collapsed, as will be readily understood.

Hingedly connected with the under side of the bottom disk 1 are supporting and clamping members 3 4, which have been shown as 80 being in the form of legs arranged in pairs at opposite sides of the disk, the supporting members 3 and 4 being normally spaced apart at their free ends by means of springs 5. The pairs of members 3 3 and 4 4 are connected by 85 cross-pieces 6 7, having right and left hand threaded apertures for the passage of a right and left threaded rod 8, having a thumb-piece or handle 9, whereby it may be manipulated to cause the clamping members to engage a suitable support, such as a portion of the casing of a piano or a parlor-organ. The legs or members 3 and 4 are preferably covered or padded with rubber or other suitable flexible material, as shown at 10, for the purpose of avoiding 90 marring of the article to which it is applied. The cross-pieces 7 have been shown as provided with points or prongs 11, engaging the

members 3 4, with which they are in this manner connected, the parts being held in mutual engagement by the tension exerted by the springs 5.

5 Supported upon the uppermost disk 1 of the bracket is a lamp, which has been shown as consisting of an ordinary cylindrical bowl 12, equipped with burner and other fixtures of ordinary construction, and provided near its 10 lower edge with an annular groove 13, in which is fitted an annular ring or wire 14, the ends of which are twisted together and bent upward to form an arm 15, supporting a reflector 16, which latter, being thus supported, 15 may be readily adjusted upon the lamp to reflect the light in any desired direction. When the device is used as a bracket-lamp, it may be extended, as shown in Fig. 1, to various positions. The bracket-disks are provided 20 with stop means, such as pins 16^a, for the purpose of limiting their movement when folded together. Said pins are disposed within the marginal edges of the several disks and are so positioned that the disks will fold 25 together symmetrically, each disk being, as hereinbefore stated, of smaller diameter than the disk next below, so that the superimposed disks, when arrested by the stop-pins 16^a, will be concentric with the subjacent disks. When 30 the bracket is thus folded, as in Fig. 3, the bracket members may be locked together by means of a pin 17, supported slidably upon the lamp-bowl, which is provided with a loop or eye 18 for the reception of said pin, the 35 latter being thus supported in alinement with perforations 19, formed in the several bracket-disks, the several perforations being in alinement with each other when the disks are folded together, as shown in Fig. 3. The pin 40 17 is provided at its upper end with a lateral extension 20, forming a hook, which is adapted to engage a stud 21 upon the side of the lamp-bowl, whereby it may be supported in a raised position, as shown in Fig. 1.

45 In Figs. 4 and 5 of the drawings a modified form of the invention has been illustrated. Under the modification the legs (here designated 25) are hinged upon pins 26, extending transversely through sockets 27 in the under 50 side of the bottom disk. Cross-pieces 28 are connected pivotally with the opposite pairs of legs, and said cross-pieces are perforated for the passage of a right and left threaded screw 29, whereby the pairs of legs may be moved 55 toward or from each other, springs being dispensed with. In this modified form the bottom disk has also been shown provided with a bracket-clamp 30, whereby it may be clamped 60 upon a stand, ledge, shelf, or table, such as a sewing-machine table, where it may thus be positioned to illuminate the work without interfering with the operator.

This improved bracket-lamp, as will be seen, is capable of being securely clamped upon the

frame or casing of a piano or organ at either 65 side of the keyboard, thus enabling it to be readily adjusted, so that the light may be reflected directly upon the music in front of the performer, or it may be secured upon stair-balusters or in any desired position where 70 proper supporting means may be had. By loosening the screw 8 it may be easily and quickly detached and utilized as an ordinary table-lamp.

From the foregoing description, taken in 75 connection with the drawings hereto annexed, the operation and advantages of this invention will be readily understood. The construction of the device is simple and inexpensive, and it will be found useful and efficient for the purposes set forth.

Having thus described the invention, what is claimed is—

1. A bracket-lamp comprising a plurality of pivotally-connected leaves of gradually-decreasing size from the bottom upward and provided with stop-pins extending upwardly within the marginal edges of said disks with the exception of the uppermost disk; and a lamp permanently secured upon said uppermost disk. 90

2. An extension-bracket lamp comprising a plurality of pivotally-connected leaves, a lamp permanently secured upon the uppermost leaf, supporting members hingedly connected with the under side of the bottom leaf, and clamping means for forcing said supporting members in the direction of each other. 95

3. An extension-bracket lamp comprising a plurality of pivotally-connected leaves; a lamp permanently secured upon the uppermost leaf, 100 supporting members hingedly connected with the under side of the bottom leaf, springs forcing said supporting members apart, and clamping means for forcing said supporting members in the direction of each other. 105

4. An extension-bracket lamp comprising a plurality of pivotally-connected leaves, a lamp permanently secured upon the uppermost leaf, pairs of legs hingedly connected with the under side of the bottom leaf, cross-pieces engaging each pair of legs and having threaded apertures, and a right and left threaded screw extending through said apertures. 110

5. An extension-bracket lamp comprising a plurality of pivotally-connected leaves, a lamp permanently secured upon the uppermost leaf, pairs of legs hingedly connected with the under side of the bottom leaf, cross-pieces engaging each pair of legs and having threaded apertures, a right and left threaded screw extending through said apertures, and spring means forcing the free ends of said legs apart. 115

6. An extension lamp-bracket comprising a plurality of pivotally-connected leaves having apertures adapted to register when said leaves are collapsed, in combination with a locking device adapted to engage said apertures, and a lamp supported upon the uppermost leaf. 125

7. In a device of the class described, an extension-bracket comprising a plurality of pivotally-connected leaves superimposed one upon another, said leaves being provided with 5 perforations adapted to register when the leaves are collapsed, in combination with a lamp permanently supported upon the uppermost leaf, and a pin or locking member slidably connected with said lamp in registry with 10 the perforations in the disks.

8. An extension lamp-bracket comprising a plurality of pivotally-connected leaves, and stop means extending upwardly from said leaves to limit the pivotal movement of said 15 leaves.

9. An extension lamp-bracket comprising a plurality of pivotally-connected leaves, a lamp permanently secured upon the uppermost leaf, stop means to limit the pivotal movement of 20 said leaves, and means for locking said leaves together when collapsed.

10. In a device of the class described, an extension-bracket including a plurality of pivotally-connected leaves having perforations to 25 receive a locking-pin, a lamp permanently

supported upon the uppermost leaf, a locking-pin slidably supported upon the bowl of the lamp and having a lateral extension or hook, and a stud upon the lamp-bowl adapted to support the locking-pin by engaging the 30 lateral projection of the latter.

11. In a device of the class described, an extension-bracket including a plurality of pivotally-connected leaves having stop means to limit their pivotal movements and perforations to receive a locking-pin, a lamp permanently supported upon the uppermost leaf, a locking-pin slidably supported upon the bowl of the lamp and having a lateral extension or hook, and a stud upon the lamp-bowl adapted 35 40 to support the locking-pin by engaging the lateral projection of the latter.

In testimony that I claim the foregoing as my own I have hereto affixed my signature in the presence of two witnesses.

JAMES ALBERT LOOMIS.
